UNITED STATES PATENT OFFICE.

OWEN H. SINGLETON, OF MONTGOMERY, ALABAMA.

APPARATUS FOR CLEANING PIPES.

1,331,681.

Specification of Letters Patent. Patented Feb. 24, 1920.

Application filed April 18, 1919. Serial No. 291,166.

To all whom it may concern:

Be it known that I, OWEN H. SINGLETON, a citizen of the United States, and a resident of the city and county of Montgomery, State of Alabama, have invented 5 certain new and useful Improvements in Apparatus for Cleaning Pipes, of which this is a specification, reference being had to the accompanying drawing, forming part

10 hereof.

The invention relates to apparatus intended for use in removing scale, incrustation, or the like from pipe lines, such as gas pipes, water pipes, and the like. The object 15 of the invention is to produce a novel, simple, and efficient apparatus for the purpose intended and which may be advantageously employed for cleaning pipes buried in the earth and where the expense of removal 20 would be great. These objects are all attained in the means shown herein and the apparatus has been found to be of extraordinary efficiency and economy in use.

The drawing shows the invention, the 25 view in Figure 1 being of the entire apparatus, except such parts shown as partly broken away, and in operative position, and Fig. 2 a cross-section on line 14—14 showing a plurality of cutters instead of only 30 two.

In the drawing 1 is a length of pipe or tubing, preferably steel, of considerably smaller diameter than the pipe to be cleaned; it being understood that apparatus 35 will be particularly adapted to clean one size of pipe only, say 4", 6", 8", etc. This tube 1 is several times its diameter in length and is provided, preferably, (always where it is to be pushed) with a tapered 40 nozzle 2 at its front end. Slots as at 3, 3, 3, are cut in its sides. Only two pairs of such slots are shown, set, as will be seen, at angles of 90 degrees. This is merely for clearness in the figure and for lack of space. 45 In practice it is intended to have at least six such pairs of slots, all having different angular positions, and while more may be employed six will generally be sufficient. At 4, 4, are shown cutters or toothed wheels, 50 it being understood that a similar wheel is disposed in each pair of slots. These cutters are journaled on pins as at 5 held in suitable openings in the wall of tube 1. The structure will be obvious from the 55 figure. The shape of these cutter teeth is material: it being found in practice that a

tooth shape substantially similar to that shown—that is to say, like a sharpened gear tooth—is best. The cutter wheels are arranged in a series from front to rear of 60 increasing diameter, that of the first being only slightly larger than the diameter of tube 1, while that of the last is very nearly as large as the inside diameter of the pipe to be cleaned. To the rear of tube 1 a reducing coupling 6 is fixed to which leads a pipe 7 by which the apparatus may be shoved along the pipe to be cleaned and through which water may be fed. Coupled by union 8 is a suitable member as at 9, 9, 65 whereby the pipe 7 may be dragged forward so as to push the tube 1 farther into the pipe being cleaned. 10 is a suitable hose connection through which water may be supplied. 75

For cleaning water mains or gas mains without pressure (as where supply is cut off) the device is used with such parts as have been described. A suitable excavation having been made and a length of the main 80 pipe removed the apparatus is assembled and connected to a water supply, say of about 60 to 75 pounds pressure, and the cutter head or tube 1 introduced into the end of the main and pushed in by force—85 two to four men usually being well able to do this work even without hand holds or other grips on pipe 7. In this pushing the cutters 4, 4, etc., function in this way: being extended through two sides of the pipe 1 90 they are necessarily in engagement with the incrustation or scale inside the main on two sides. This necessitates that if they roll, as against a rack, they must cut with the opposite teeth against the other side of the incrust- 95 ed pipe. In practice it is found that the cutters work very perfectly this way; first cutting against one side and then against the other—the cutting being done always by that part of the wheel which is slipping and 100 the driving of the cutter being effected by the gripping of the cutter teeth on the opposite side. In effect the push given by the men on the pipe 7 is translated into rotary movement of the toothed cutters. The 105 distinct advantage of the cutters disposed in this way is that so soon as a cutter jams with the teeth which have just been cutting, it begins to roll on those teeth and cut with the teeth opposite. It has not been found 110 necessary to give to the cutter teeth any special shape except as indicated. In actual

construction it has been found that to clean a 4" gas main the cutters are very satisfactory if made of 1" steel, hardened only on the teeth and running on approximately $\frac{3}{8}$ " diameter pins. The tube 1 should in such case be approximately 1 $\frac{1}{4}$ " heavy wrought iron pipe—steel being better but not essential—as such strain as may be put on the cutter head is limited to the amount which 10 the water pipe 7 can sustain. It will be understood that whenever the supply pipe 7 is pushed in an entire length, union 8 is loosened, and a second length inserted. This 15 obviously, is necessary because of the space limits of the excavation at the end of the main. In practice it is found that a crew of three or four men can easily clean several hundred feet per day of badly fouled gas main—4" being understood. Larger sizes 20 would doubtless be handled slower.

In cleaning gas mains where gas under pressure is present I prefer to employ a plug as at 12, say a tapered bit of wood, partly shown in section and fitted into the end of 25 the pipe—see dotted lines 11, 11. A gasket or packing, also shown in part section, as at 13, is a rubber disk, centrally perforate, and adapted to closely fit the pipe 7 but still to permit sleeves on pipe 7, as it is lengthened, to pass. The central opening through 30 plug 12 must, of course, be large enough to permit such sleeves to pass freely.

For extra large sizes of pipes where it is 35 inexpedient or difficult, on account of the resistance, to push the cutter head through

the pipe a wire rope may be first threaded through the length of pipe to be cleaned, as by successively jointed lengths of light pole, and the cutter head then dragged through by this rope and a windlass. This method 40 of operation is so fully obvious as to need no illustration. Of course the water supply may be maintained through pipe 7 whether that pipe or a rope be used to force the cutter head along.

While ordinarily it will be found sufficient to permit the debris to escape to the front—the nozzle at 2 serving to help the escape in this direction—it is easily possible where the pipe is too completely obstructed 50 to permit the debris to return with the waste wash-water to the end of the pipe from which the operation is begun.

Having described my invention, what I claim is:

A tube cleaner consisting of a head having a series of longitudinally extending slots arranged spirally therein, a series of rotatable saws mounted in said slots and extending longitudinally of said head and each saw 60 having teeth projecting from opposite sides of said head, the teeth of the different saws extending unequal distances from said head.

Witness my hand this April 12, 1919.

OWEN H. SINGLETARY.
